(57) **CLAIM**

We claim the ornamental design for a luminaire, as shown and described.

DESCRIPTION

FIG. 1 is a first perspective view of a luminaire according to a new design.

FIG. 2 is a second perspective view of the luminaire of FIG. 1.

FIG. 3 is a third perspective view of the luminaire of FIG. 1.

FIG. 4 is a first side elevation view of the luminaire of FIG. 1.

FIG. 5 is a second side elevation view of the luminaire of FIG. 1.

FIG. 6 is a third side elevation view of the luminaire of FIG. 1.

FIG. 7 is a fourth side elevation view of the luminaire of FIG. 1.

FIG. 8 is a top plan view of the luminaire of FIG. 1; and, FIG. 9 is a bottom plan view of the luminaire of FIG. 1. The elements shown in broken lines are included for the purpose of illustrating portions of the luminaire that form no part of the claimed design.

1 Claim, 9 Drawing Sheets
